UNITED STATES PATENT OFFICE.

CHARLES MARTIN BAGSHAW, OF LEICESTER, ENGLAND, ASSIGNOR TO THE GIMSON SHOE MACHINERY CO., LIMITED, OF LEICESTER, ENGLAND, A BRITISH COMPANY.

LASTING MACHINE.

Application filed September 26, 1922. Serial No. 590,601.

To all whom it may concern:

Be it known that I, CHARLES MARTIN BAGSHAW, a subject of the King of Great Britain, of Laburnum Road, Old Humberstone, Leicester, England, have invented an Improvement in or Relating to Lasting Machines, of which the following is a specification.

This invention relates to lasting machines of the bed lasting type wherein the edge of the upper is turned over and ironed down by means of movable wiper plates, and its object is to construct an improved form of machine intended for lasting the heel seat of the work.

The invention consists of a lasting machine of the above mentioned type having, in combination, movable wiper plates for turning the edge of the upper over upon the insole, means for inserting a plurality of fastening tacks through the wiper plates and edge of the upper to secure the latter, a heel clamp to engage the upper round the back and sides, and automatically acting means to effect close engagement of the work and the heel clamp whereby the latter is caused to firmly hold the upper to the back and sides of the last during the wiping action of the wiper plates and mould and shape the upper to last in this region.

The combination just referred to constitutes an important improvement as it enables the machine, at one operation, to mould and shape the back and sides of the upper to the last, hold said upper in this region to prevent slip of same on the last, and turn over and secure the edge of the upper.

It has been previously proposed in a bed lasting machine, for the purpose of driving a plurality of tacks through each wiper plate to secure the lasted upper, to provide the wiper plates with a series of nozzles and a corresponding series or group of drivers arranged to be reciprocated by any suitable means, said nozzles being rigid on the wiper plates and moving with them.

In the machine of the present invention, for inserting the fastening tacks there is provided a series of driver tubes each containing tack feeding and driving means, the lower extremities of said tubes communicating with holes in and being mounted upon the wiper plates so as to be capable of move-

ment relatively thereto as well as movement therewith. The upper ends of the driver tubes are held by a device which allows them to oscillate and slide therein when the lower extremities move with the wiper plates.

It is also a feature of the invention that each driver tube has a driver bar projecting from its upper end and there is provided in association therewith a member common to all the driver bars for operating them simultaneously for driving the tacks, said member being operated by power actuated means.

In further describing the invention reference will be made to the accompanying drawings wherein:—

Figure 1 is a side elevation of an organized machine embodying the invention.

Figure 2 is a half sectional plan of the heel clamp and wiper plate mechanism in normal position.

Figure 3 is a similar view showing the wiper plates advanced as in operation.

Figure 4 is a side elevation of the parts shown in Figure 3, but with the wiper plates retracted.

Figure 5 is an elevation of the cam arrangement for operating the driver lever.

Figure 6 is an elevation of the drive controlling means.

Figure 7 is a front elevation of the wiper mechanism and the associated tack delivering means.

Figure 8 is a vertical section of one of the driver tubes and the parts associated therewith.

Figure 9 is a front elevation of three adjacent driver tubes.

Figures 1, 5 and 7 are drawn to a smaller scale than the other figures, and throughout the drawings like parts are designated by the same reference characters.

In the machine shown in the drawings as an example of the invention, the last, represented at 1 in Figure 1, is supported in a horizontal position, bottom upwards, by a jack 2 adjustably attached to a post 3 slideable up and down in a bearing 4 pivotally carried at 5 on the machine frame 6. The post 3 falls by its own weight and rests upon a step 7 supported by a spring 8 in a lever 9 operable by a rod 10, lever 11 and cam 12 for raising the post and jack at the time required. A treadle (not shown) may be con-

nected with the lever 9 or some associated part for raising the post independently of the cam. By means of the spring 8 the work on the last is yeldingly pressed up 5 against the underside of the wiper plates (hereinafter referred to) when the post and jack are raised.

The jack 2 carries an adjustable toe support 13 adjustable bodily along an arm 14 10 in relation to a pin 15 on which the last is placed. Vertical adjustment of the jack 2 on the post 3 is effected by rotation of a handwheel 16.

Located in a recessed part 17 (Figure 7) 15 of the machine frame 6 and attached to an upper structure 18 on the latter is a bed 19. This bed (Figures 1, 2, 3 and 4) carries a heel clamp 20 furnished with a flexible band 21 for engaging the back of 20 the work. The clamp 20 is slidably adjustable in the bed in a forward and backward direction the position being determined by a screw 22 with which a shoulder 23 on the clamp makes contact. The jack 2 is connected with a lever 24 by means of a coupling device 25 the said lever being fulcrumed at 26 and acted upon by the arm 27 of a bell-crank lever 28 mounted upon the same fulcrum. To the arm 29 of the lever 25 30 is connected a rod 30 attached at its opposite end to a treadle 31. Depression of the treadle 31 causes the coupling device 25 to pull the jack towards the machine frame thereby pressing the back of the heel 35 part of the work into engagement with the flexible part 21 of the heel clamp and forcing the toe of the last down upon the toe rest 13 so that the work is firmly held.

Mounted to slide within the bed 19 is a 40 housing or box 32 (Figures 2, 3 and 4) having therein wiper plates 33 removably carried by holders 33^a arranged to slide in arcuate guideways in the box so as to give the plates a relative closing and opening 45 movement as represented in Figures 3 and 2 respectively. The housing or box 32 is moved backwards and forwards horizontally to bring the wiper plates into and out of position over the heel seat of the work 50 supported on the aforesaid jack. This movement is imparted by means of an eccentric 34 on a cam shaft 35, (Figures 1 and 4) operating in conjunction with springs 36 the latter being disposed one on 55 each side of the eccentric and suitably arranged to draw the box backwards from the work and the eccentric operates through the medium of a telescopic connecting rod 37 to push the box forward. The opening and 60 closing movements of the wiper plates 33 are imparted by means of racks 38 (Figures 2 and 3), pinions 39 and a rack 40. The racks 38 slide on the bed 19 and are connected to the wiper plate-holders 33^a by 65 links 41; the rack 40 is fixed on the bed

19; and the pinions 39 are mounted upon pins 42 in the box 32 so that they move with the latter and by engagement with the fixed rack 40 are rotated and transmit sliding movement to the racks 38.

A handlever 43 (Figures 2, 3, 4 and 7) is provided for initially moving the box and wiper plates forward to try the setting of the work in relation to wiper plates before the machine is started. For this purpose 75 the before mentioned rod 37 is formed to permit a certain amount of free movement of the box to take place. The end 44 of said rod which is pivotally connected to the box at 45 (Figure 4) is formed to slide within a hole 46 in the rod 37. A hand nut 47 adjustable on a screw threaded part of said end 44 constitutes an abutment to take the thrust of the tubular rod 37 when the latter moves forward.

Each wiper plate 33 has a series of holes 48 (Figures 2, 3 and 8) through which the tacks are driven into the turned over edge of the upper. Each hole on the upper face of the plate opens out into a recess or cup 49 in which the lower rounded extremity of a driver tube 50 rests. The several driver tubes 50 pass at their upper ends through holes 51 in a bracket 52 (Figures 1, 7 and 8) fixed to the before mentioned upper structure 18 said holes being rounded as shown in Figure 8 to allow the tubes to oscillate and slide therein as the lower extremities of said tubes follow the movements of the wiper plates. The driver tubes 50 are retained in position by their own weight.

Each driver tube contains a driver bar 53 slidable therein and carrying at its lower end a driver 54. A spring 55 normally holds the driver bar raised with its upper end projecting beyond the top of the driver tube. Each driver tube has a tack throat 56 at its lower end which communicates with the hole in the wiper plate. An inclined tack feeding passage 57 is formed through the side of the driver tube and at one end leads into the tack throat 56 while at the other end it is in communication with a flexible delivery tube 58 which is connected with a tack supply box or apparatus of suitable character (not shown). Each tack after being delivered to the throat 56 is held in the latter as represented at 59 by a device, such for example as a bevelled pin 60 carried by a spring 61, capable of yielding when the driver 54 descends.

Pivotsly mounted at 62 in the upper structure 18 (Figure 1) and situated above the upper ends of the several driver bars 125 53 is a driver lever 63 with which is connected a strong spring 64. This lever is provided with a series of adjustable tappets 65 one for contact with each driver bar. The downward movement of the lever 130

63 is limited by an adjustable stop 66 therein which engages with a suitable pad 67 on the bracket 52.

The driver lever 63 is moved to a normal set position, shown in Figure 1, in which its spring 64 is tensioned, by a pivoted catch 68 (Figures 1 and 5) on a slide rod 69 actuated by a cam 70 on the aforesaid shaft 35. The catch engages with a nose 71 on the lever 63 and is turned on its pivot 72 by the engagement of a block 73 adjustably mounted by a pin 73^a on the cam 70 with an arm 74 attached to said catch. When thus turned the catch 68 suddenly releases the lever 63 which is thereupon moved by its spring 64 and strikes the several driver bars 53 thus forcing down all the drivers to insert the tacks.

In the complete operation of the machine, a last with the upper assembled is placed on the last pin 15 and the treadle 31 is depressed to move the post 3 on its pivot 5 and carry the work lightly into contact with the heel band 21 of the heel clamp 20. The operator is then able to judge whether the work is at the correct height for the wiper plates 33 to iron the upper and stiffening down tightly on the last when they subsequently move forward. An adjustment of the work to obtain the correct relation between the work and the wiper plates may be made, if necessary, by rotation of the hand-wheel 16. The toe support 13 may be raised or lowered to bring the heel seat of the work approximately parallel to the wiper plates. For some classes of work the toe support may be discarded in which cases the operator will hold the work level as the wiper plates operate.

The weight of the work, jack and post is taken by the spring 8 in the lever 9, which at this stage is held in position by the rod 10, lever 11 and cam 12. The machine is now started by actuation of a starting handle 75 (Figures 1 and 6) whereupon a cam 76 on the shaft 35 acts upon the before mentioned lever 24 and, by means of the coupling device 25, draws the back of the work into close engagement with the heel clamp. The coupling device has a strong spring 77 combined with it through which the drawing action just mentioned is transmitted so that the lever 24 acts in a yielding manner and thus enables the work to accommodate itself to the position to which the heel clamp has been adjusted by the screw 22. The adjustment of the heel clamp by the said screw regulates the distance at which the tacks are inserted from the edge of the work.

The cam 76 is timed to impart the backward pressure before the wiper plates operate on the work. The eccentric 34 comes into operation to move the slide box 32 forward thus carrying the wiper plates 33 over the heel seat and causing them at the same

time to close towards each other to iron and wipe over the upper and press it down upon the last. Just about the time that the wiper plates reach their fully operative position over the heel seat, the lever 9 is operated by the cam 12 to impart a strong upward pressure on the post 3 so that the wiped over upper is pressed upwards against the underside of the wiper plates. This upward pressure is, it will be noticed, transmitted to the post 3 through the before mentioned spring 8 which, prior to the actuation of the lever 11 by the cam 12 and when there is no initial tension on, is capable of yielding slightly, if necessary, while the wiper plates are passing over the work.

After the cam 12 has operated in the manner just described to apply the full upward pressure to the work and before the lever 63 is tripped to drive the tacks, the machine may, if desired or necessary, be stopped by the operator. When the work is difficult or a very flat heel seat is required the stoppage of the machine at the above stage may be necessary or desirable to enable the upward pressure against the wiper plates to have full effect. This stoppage is rendered possible by the provision in a clutch controlling cam 78 (Figure 6) of two gaps 79, 80. These gaps allow the controlling handle 75 to be actuated upon by its spring 81 at each half revolution of the cam shaft 35. If it is not desired to stop the machine at the half revolution, the operator holds the handle so that the roll 82 thereon does not drop into the corresponding gap in the cam 78.

After the upward pressure has been applied and, if the machine has been stopped after it has been re-started, the block 73 on the cam 70 makes contact with the arm 74 and knocks the catch 68 off the nose 71 thereby releasing the lever 63 which is actuated to drive the tacks as already described.

After the tacks are driven, the cam 12 allows the post 3 to drop to a lower position than the normal one thereby bringing the work down quite clear of the wiper plates. In the meantime the cam 76 moves around to a position which releases the back pressure i. e. the pull on the jack so that the latter with the post falls outwards thus carrying the work away from the heel clamp to a convenient position for removal by the operator.

The before mentioned handle 43, may, in addition to being used for the aforesaid purpose, be used for bringing the wiper plates forward by hand to partially break down the upper and stiffener before the machine commences to operate under power.

Adjustment of the hand nut 47 on the telescopic rod varies the length of movement of the wiper plates by providing more or less lost motion between the parts 37 and 44 and this also varies the angle to which

the said plates turn in the slide box 32 thereby enabling suitable regulation to be made for lasts of various sizes.

The telescopic connection between the box 5 32 and its actuating eccentric 34 also serves to allow the box to remain in the advanced position until the upward pressure on the wiper plate is released whereupon the springs 36, which also allow the box to be 10 held in the forward position by the upward pressure, act to draw the box backwards. This arrangement obviates the friction which would otherwise be engendered if the eccentric commenced to pull the box back 15 before the upward pressure was relieved.

What I claim then is:—

1. A boot or shoe lasting machine of the bed lasting type having, in combination, movable wiper plates for turning the edges 20 of the upper over upon the insole, means for inserting a plurality of fastening tacks through the wiper plates and edge of the upper to secure the latter, a heel clamp to engage the upper round the back and sides, 25 said means comprising a series of driver tubes each containing tack feeding and driving means, the lower extremities of said tubes communicating with holes in and being mounted upon the wiper plates so as 30 to be capable of movement relatively thereto as well as movement therewith, and automatically acting means to effect close engagement of the work and the heel clamp whereby the latter is caused to firmly hold 35 the upper to the back and sides of the last during the wiping action of the wiper plates and mould and shape the upper to the last in this region.

2. A boot or shoe lasting machine of the bed lasting type having in combination, 40 movable wiper plates for turning the edges of the upper over upon the insole, means for inserting a plurality of fastening tacks through the wiper plates and edge of the upper to secure the latter, a heel clamp to engage the upper round the back and sides, 45 said means comprising a series of driver tubes each containing tack feeding and driving means the lower extremities of said tubes communicating with holes in and being mounted upon the wiper plates so as to be 50 capable of movement relatively thereto as well as movement therewith, automatically acting means to effect close engagement of the work and the heel clamp whereby the latter is caused to firmly hold the upper to the back and sides of the last during the 55 wiping action of the wiper plates and mould and shape the upper to the last in this region, and a device which holds the upper ends of the aforesaid driver tubes and allows them to oscillate and slide therein when the lower extremities move with the wiper plates.

3. A boot or shoe lasting machine of the

bed lasting type having, in combination, movable wiper plates for turning the edges of the upper over upon the insole, means for inserting a plurality of fastening tacks through the wiper plates and edge of the upper to secure the latter, a heel clamp to engage the upper round the back and sides, 70 said means comprising a series of driver tubes each containing tack feeding and driving means the lower extremities of said tubes communicating with holes in and being mounted upon the wiper plates so as to be capable of movement relatively thereto as well as movement therewith, automatically 75 acting means to effect close engagement of the work and the heel clamp whereby the latter is caused to firmly hold the upper to the back and sides of the last during the wiping action of the wiper plates and mould and shape the upper to the last in this region, the lower extremities of the aforesaid driver tubes being rounded and resting in recesses formed in the wiper plates, and a device which holds the upper ends of said tubes, 80 said tubes passing through holes in said holding device which allows them to oscillate and slide therein when the lower extremities move with the wiper plates.

4. A boot or shoe lasting machine of the bed lasting type having, in combination, 95 movable wiper plates for turning the edges of the upper over upon the insole, means for inserting a plurality of fastening tacks through the wiper plates and edge of the upper to secure the latter, a heel clamp to engage the upper round the back and sides, 100 said means comprising a series of driver tubes each containing tack feeding and driving means the lower extremities of said tubes communicating with holes in and being mounted upon the wiper plates so as to be capable of movement relatively thereto as well as movement therewith, and automatically 105 acting means to effect close engagement of the work and the heel clamp whereby the latter is caused to firmly hold the upper to the back and sides of the last during the wiping action of the wiper plates and mould and shape the upper to the last in this region, each of the aforesaid driver tubes having a driver bar projecting from its upper end and there being provided in association therewith a member common to all the driver bars for operating them simultaneously for driving the tacks, said member 110 being operated by power actuated means.

5. A boot or shoe lasting machine of the bed lasting type having, in combination, movable wiper plates for turning the edges of the upper over upon the insole, means for inserting a plurality of fastening tacks through the wiper plates and edge of the upper to secure the latter, a heel clamp to engage the upper round the back and sides, 115 said means comprising a series of driver 120 tubes each containing tack feeding and driving means the lower extremities of said tubes communicating with holes in and being mounted upon the wiper plates so as to be capable of movement relatively thereto as well as movement therewith, and automatically 125 acting means to effect close engagement of the work and the heel clamp whereby the latter is caused to firmly hold the upper to the back and sides of the last during the wiping action of the wiper plates and mould and shape the upper to the last in this region, each of the aforesaid driver tubes having a driver bar projecting from its upper end and there being provided in association therewith a member common to all the driver bars for operating them simultaneously for driving the tacks, said member 130 being operated by power actuated means.

- tubes each containing tack feeding and driving means the lower extremities of said tubes communicating with holes in and being mounted upon the wiper plates so as to 5 be capable of movement relatively thereto as well as movement therewith, and automatically acting means to effect close engagement of the work and the heel clamp whereby the latter is caused to firmly hold 10 the upper to the back and sides of the last during the wiping action of the wiper plates and mould and shape the upper to the last in this region, the aforesaid driver tubes having driving bars projecting from their upper ends which bars are operated by a member common to all and consisting of a lever provided with a series of independently adjustable tappets, one for contact with each driver bar, said lever being moved to normal set position by cam-actuated means and moved for operating the driver bars by a spring, said cam-actuated means including a pivoted catch on a cam-actuated slide, said catch holding the lever with its spring tensioned and being moved by a cam to release 50 said lever for actuating the drivers. 55
6. A boot or shoe lasting machine of the bed lasting type having, in combination, movable wiper plates for turning the edges of the upper over upon the insole, means for inserting a plurality of fastening tacks through the wiper plates and edge of the upper to secure the latter, a heel clamp to engage the upper round the back and sides, and automatically acting means to effect close engagement of the work and the heel clamp whereby the latter is caused to firmly hold the upper to the back and sides of the last during the wiping action of the wiper 60 plates and mould and shape the upper to the last in this region, said automatically acting means consisting of a post carrying a jack for the work arranged to move about a pivot the indraw movement being imparted to 65 said post by means comprising a lever, a cam for moving said lever, a coupling device connecting said lever and post and a spring combined with said coupling device through which the drawing action is yieldingly transmitted from the lever to the post, said post, for the purpose of pressing the work against the face of the wiper plates, being also slidably actuated by means comprising a lift lever, a yielding step in said 70 lever for engaging the post, a second lever, a cam to actuate the latter, and a rod connecting the second lever with the lift lever. 75
7. A boot or shoe lasting machine of the bed lasting type having, in combination, movable wiper plates for turning the edges of the upper over upon the insole, means for inserting a plurality of fastening tacks through the wiper plates and edge of the upper to secure the latter, a heel clamp to engage the upper round the back and sides, and automatically acting means to effect close engagement of the work and the heel clamp whereby the latter is caused to firmly hold the upper to the back and sides of the last during the wiping action of the wiper 80 plates and mould and shape the upper to the last in this region, the aforesaid driver tubes having driving bars projecting from their upper ends which bars are operated by a mem- 85

In testimony whereof, I have signed my name to this specification. 90

CHARLES MARTIN BAGSHAW.
